FLOOR MAINTENANCE MACHINE

William E. Holt, Oakland, Calif.

Application July 27, 1945; Serial No. 607,297

6 Claims. (Cl. 15—49)

1.

The present invention relates to the construction and operation of floor maintenance machines, and more particularly to machines of the character described comprising a motor driven floor surfacing element arranged to rotate about a vertical axis when in use.

The rotary surfacing element of such machines normally consists of a brush member having an annular wooden base detachably secured in a predetermined position to a rotary drive element and in which base tufts of wire, hair or fiber are embedded in any suitable manner. The tufts are initially positioned and trimmed to provide a level brushing surface as well as to dynamically balance the brush member. If, however, the tufts are improperly trimmed or wear unevenly or tufts are lost, the brush member is thrown out of dynamic balance and tends to wobble relative to the drive mechanism. The effect is usually cumulative and tends to cause rapid and uneven wearing of the tufts. Also, when machines of this type are used on rough or irregular floor surfaces, the brush member often tends to whip or hop, producing an uneven surfacing effect and imposing undesirable torque stresses on the drive mechanism.

The general object of my invention is the provision of a floor maintenance machine having an improved drive connection between the drive mechanism and rotary surfacing element which tends to keep torque stresses on the drive mechanism due to uneven brushing or floor surfaces at a minimum and thus provide a long life for both the rotary surfacing element and drive mechanism. A further and more specific object is the provision of an improved form of connecting bracket which provides a self-leveling detachable drive connection between the rotary surfacing element and the drive mechanism.

The various features of novelty which characterize my invention are pointed out with particularity in the claims annexed to and forming a part of this specification. For a better understanding of the invention, its operating advantages and specific objects attained by its use, reference should be had to the accompanying drawing and descriptive matter in which I have illustrated and described a preferred embodiment of my invention.

Of the drawings:

Fig. 1 is an elevation of a portion of a floor maintenance machine of the general type to which my invention is applicable;

Fig. 2 is an enlarged view of portions of the drive mechanism and brush member, with parts

broken away and in section on the line 2—2 of Fig. 4;

Fig. 3 is a vertical section taken on the line 3—3 of Fig. 2;

Fig. 4 is a bottom view of the drive connection; and

Fig. 5 is a bottom perspective of the connecting bracket.

In the floor maintenance machine illustrated 10 a wheeled carriage is formed by an annular downwardly flaring casing 10, on the rear side of which a pair of supporting wheels 11 are tiltably mounted. An inclined integral socket 12 projects rearwardly from the casing 10 and receives a hollow handle member 13 by which the machine is directed by the operator. The handle member serves as a conduit for the electrical connections 14 from any suitable power source, to an electric motor 15 mounted on the casing 10. A cap weight 16 is mounted on the motor. The electric motor 15 is arranged with its drive shaft 20 vertical and symmetrically projecting downwardly through the center opening in the casing 10. A downwardly tapering stepped shell 21 surrounds the shaft 20 25 and is formed with a horizontal annular flange 22 at its upper end which is rotatably supported on the casing 10. The shell has a bottom section 23 in which a hub 24 is formed. The hub serves as a journal for the lower end of the drive shaft 20. Rotation of the shell is effected by a spur gear 25 on the shaft 20 driving an internal gear 26 on the shell through idler gears 27 in a well-known manner.

The rotary surfacing element shown in a brush member 30 comprising an annular wooden base 31 in which a multiplicity of tufts 32 of wire, fiber or hair are embedded and trimmed to form a level brushing surface. In accordance with my invention, a readily detachable drive connection 35 between the lower section 23 of the rotary shell and the brush member 30 is established by a special bracket 40 which fits into the circular opening 33 in the base 31 and is supported in that position by projecting flanges 41 which rest on and are secured to the upper surface of the base by screws 42. At three symmetrically spaced points on the underside of the bracket substantially opposite to the flanges 41, integral lugs or stop members 43 extend downwardly. The lugs 45 have a flat vertical face 43 on one side and at the opposite side taper towards the surface of the bracket. At symmetrically arranged points intermediate the lugs 43, the inner edge of the bracket is cut away to form outwardly tapered recesses 45. Between each of the recesses 45 and

50 the lugs 43 are spaced by a distance equal to the width of the recesses 45.

the adjacent lug face 43^a, a relatively stiff flat spring 46 is secured at one end to the underside of the bracket adjacent the corresponding recess with its free end downwardly bent away from the bracket into a substantially horizontal plane and terminating adjacent the lug face 43^a. At symmetrically spaced points on the periphery of the lower shell section 23 corresponding to the location of the recesses 45, short integral lugs 47 of substantially rectangular cross-section and a shape permitting passage through the recesses 45, project from the shell with their upper surfaces at a level corresponding to the level of the plane of the flat springs 46.

With the described construction, the brush member 30 is readily mounted in the machine by tilting the machine and positioning the bracket recesses 45 so as to pass over the lugs 47 and then angularly moving the brush member counter to the designed direction of brush rotation until the lugs 47 pass under and in resilient contact with the springs 46 until they abut the faces 43^a of the corresponding stop members 43. In this position, the upper surface of the bracket will be in contact with the peripheral flange on the shell section 23 and the springs 46 will exert a downward pressure on the drive lugs 47. In detaching the brush member, the operation is reversed.

With the described drive connection between the motor 15 and the brush member 30, a positive drive is effected, while at the same time the resilient support of the brush member on the drive lugs 47 permits a limited movement of the brush member vertically relative to the shell 21 without disrupting the drive connection. This capacity for limited relative vertical movement between these parts allows the brush member to effect the desired surfacing action on rough or uneven floor surfaces without whipping and hopping. The resilient vertical contact of the parts tends to maintain the brushing surface in the same plane for all normal variations in tuft wear. Torque stress is kept to a minimum, insuring a long life to both the brush member and machine.

While in accordance with the provisions of the statutes I have illustrated and described herein the best form of the invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. A floor maintenance machine comprising an electric motor, a horizontally arranged rotary surfacing element, and means forming a drive connection between said motor and said rotary surfacing element including a rotary member driven by said motor, a plurality of symmetrically arranged peripheral lugs projecting from said rotary member, a bracket mounted on said rotary surfacing element and having recesses therein adapted to receive said lugs, spring means on the underside of said bracket at positions angularly adjacent said recesses and arranged to exert a resilient downward pressure on said lugs when said lugs are relatively moved through the corresponding recesses and angularly to positions below corresponding spring means, and stop members on the underside of said bracket arranged to limit the relative angular movement of said lugs and bracket.

2. A floor maintenance machine comprising an

electric motor, a horizontally arranged rotary surfacing element, and means forming a drive connection between said motor and said rotary surfacing element including a vertical drive shaft driven by said motor, a rotary shell surrounding and driven by said shaft, a plurality of symmetrically arranged peripheral drive lugs projecting from said shell, a bracket mounted on said rotary surfacing element and having recesses therein adapted to receive said drive lugs, spring means on the underside of said bracket at positions angularly adjacent said recesses and arranged to exert a resilient downward pressure on said drive lugs when said drive lugs are relatively moved through the corresponding recesses and angularly to positions below the angularly adjacent portions of said bracket, and stop means on said bracket arranged to abut said drive lugs to limit the relative angular movement of said drive lugs and bracket and provide a drive connection therebetween.

3. A floor maintenance machine comprising an electric motor, a horizontally arranged rotary surfacing element, and means forming a drive connection between said motor and said rotary surfacing element including a rotary member driven by said motor, a plurality of symmetrically arranged peripheral lugs projecting from said rotary member, a bracket mounted on said rotary surfacing element and having recesses therein adapted to receive said lugs, flat springs mounted on the underside of said bracket at positions angularly adjacent said recesses and arranged to exert a resilient downward pressure on said lugs when said lugs are relatively moved through the corresponding recesses and angularly to positions below corresponding flat springs, and stop members on the underside of said bracket arranged to limit the relative angular movement of said lugs and bracket.

4. A floor maintenance machine comprising an electric motor, a horizontally arranged rotary surfacing element, and means forming a drive connection between said motor and said rotary surfacing element including a vertical drive shaft driven by said motor, a rotary shell surrounding and driven by said shaft, a plurality of symmetrically arranged peripheral drive lugs projecting from said shell, a bracket mounted on said rotary surfacing element and having recesses therein adapted to receive said drive lugs, flat springs mounted on the underside of said bracket at positions angularly adjacent said recesses and arranged to exert a resilient downward pressure on said drive lugs when said drive lugs are relatively moved through the corresponding recesses to positions below corresponding flat springs, and integral stop members on the underside of said bracket at the opposite end of said springs from said recesses arranged to abut said drive lugs to limit the relative angular movement of said drive lugs and bracket and provide a drive connection therebetween.

5. A rotary brush support bracket having an annular body with angularly spaced recesses in the inner periphery thereof, flat springs mounted on and extending in spaced relation along the underside of said bracket at positions angularly adjacent said recesses, and a depending stop member on the underside of said bracket at the opposite end of each of said springs from said recesses.

6. A rotary brush support bracket having an annular flat body with angularly spaced recesses in the inner periphery thereof adapted to receive

corresponding drive lugs, flat springs mounted on and extending in spaced relation along the underside of said bracket at positions angularly adjacent said recesses and arranged to exert a resilient downward pressure on said drive lugs when said drive lugs are relatively moved through the corresponding recesses to positions below said springs, and depending integral stop members on the underside of said bracket at the opposite end of said springs from said recesses arranged to abut said drive lugs to limit the angular movement of said drive lugs relative to said bracket to a position below the corresponding flat springs.
